LOOM

Jonas Northrop, Hopedale, Mass., assignor to
Draper Corporation, Hopedale, Mass., a corpora-
tion of Maine

Application September 29, 1934, Serial No. 746,213

7 Claims. (Cl. 139—231)

The present invention pertains to the filling replenishing mechanism of automatic looms, and has more particular reference to the revoking devices therefor for revoking a call for replenishment when the shuttle is improperly boxed.

In the conventional automatic loom the filling replenishing mechanism is positioned for transfer while the lay is well back and the replenishing operation occurs at a later time, usually when the lay is at front center. Such looms are customarily provided with a shuttle feeler and connections therefrom for revoking or preventing the transferring operation if, on the replenishing beat of the lay, the shuttle fails to enter the shuttle box 15 to its full depth.

While the conventional shuttle feeler adequately guards against damage occasioned by the failure of the shuttle to fully enter the box, it is inoperative to prevent such damage when the 20 shuttle boxes too far. It has been proposed to so construct the shuttle feeler mechanism as to guard against damage from both of the aforesaid causes, but such prior constructions have not been satisfactory and, so far as I am aware, have 25 never been used commercially. I find it impracticable to provide a single shuttle feeler mechanism having what, in reality, amounts to two separate functions, and accordingly propose to provide a 30 separate shuttle feeler mechanism for revoking a call for replenishment when the shuttle boxes to more than its normal depth.

The shuttle cannot box too far for proper replenishment unless there exists in the loom some fixed defect such as a badly worn picker, in which 35 event the loom should not be continued in operation but should be promptly stopped and repaired. It is accordingly an object of the present invention to provide a revoking mechanism which is normally in inoperative condition but which is rendered operative whenever the shuttle boxes 40 too far, to thereafter prevent any replenishing operation taking place until the device is manually reset.

A further object of the present invention is to 45 provide, in a filling replenishing loom, a shuttle feeler and revoking mechanism controlled thereby which are normally stationary but which are movable to revoking position only when the shuttle enters the shuttle box too far to permit proper 50 replenishment to take place.

Further objects of the invention will become 55 apparent as the description proceeds.

The specific embodiment of the invention herein disclosed is applied to a bobbin changing loom 55 wherein a transfer hammer has pivoted thereto

a dog which is movable to and from position where it is engageable by a lay bunter. A second dog is connected so that, when actuated, it positively removes the first dog from operative position. The second dog is operable by a bunter 5 which is mounted on and slidably longitudinally of the lay but which is normally held in inoperative position by a latch member. A normally stationary shuttle feeler in the shuttle box is connected to release the latch when the shuttle 10 enters the box to more than its normal depth. A spring is connected to move the revoking bunter to revoking position upon release of the latch, the spring thereafter holding the bunter in revoking position until the loom is stopped and the 15 latch manually reset.

For more detailed disclosure of the said embodiment, reference may be had to the accompanying drawings, of which:

Fig. 1 is a perspective view of the right hand 20 shuttle box and contiguous parts;

Fig. 2 is a plan view of the right hand end of the lay;

Fig. 3 is a view similar to Fig. 2 but showing 25 the parts in normal or running position; and

Fig. 4 is a front elevation of the same.

The loom to which the invention has been applied is but fragmentarily illustrated on the drawings, the illustrated parts including a loom side 1, a breast beam 2, a lay 3, lay sword 4, and certain 30 parts of the filling replenishing mechanism to be more fully described. Other parts of the loom are old and well known in the art and form no part of the present invention, and accordingly are not shown or described.

The shuttle 5 is adapted to be picked along the lay as by picker stick 6 and is received at each end of its flight in a shuttle box. Only the right hand shuttle box is shown, the same being comprised of a back box plate 7 and front box plate 8 40 secured to the lay, and a binder 9. The shuttle carries a renewable filling supply, as by means of the automatically ejectable bobbin 10.

The loom is shown as being of the bobbin changing variety wherein a rotary magazine 11 45 is positioned directly over the shuttle box and the bobbins contained in the magazine are adapted to be transferred, successively, to the shuttle by a transfer hammer 12. A dog 13 is pivoted to the transfer hammer for movement to and 50 from position where it can be engaged by a lay bunter 14 to effect the actual transfer.

The dog 13 is controlled by an arm 15 through the medium of a pin 16 projecting from the side of the dog. The arm 15 moves upwardly 55

and rearwardly to raise the dog to transferring position, and is so moved by or through the usual shuttle feeler mechanism, not shown.

As is above noted, certain defects in the loom 5 will result in the shuttle entering the shuttle box to such an abnormal extent that the filling replenishing mechanism cannot effect the replenishment and will consequently damage the loom if replenishment is attempted. The defects which 10 permit the shuttle to thus box abnormally are usually such as to result in repeated or recurrent abnormal boxing of the shuttle, as distinguished from the transitory defects which cause the shuttle to fail to fully enter the box. The 15 present invention accordingly provides revoking means which is normally stationary and inoperative but which is released by the shuttle whenever, on any pick, the shuttle boxes too far. Once the revoking means is so released no replenishment can take place on the same or any subsequent 20 pick. The loom will thereupon stop from the filling fork (not shown), thus directing attention to the defective condition of the loom.

The specific revoking means shown includes a 25 bunter 17 on plate 18 which is mounted on and movable along the lay as by sliding on bolt 19 and pin 20. The bunter is normally inwardly (i. e. to the left) from a dog 21 which is mounted on a pin 22 projecting from the arm 15. The 30 bunter is held in this inoperative position by a latch 23 which is pivoted as at 24 to the lay. A tension spring 25 has one end connected to an arm on the latch and its other end connected to a pin on the plate 18. The spring thus serves the 35 dual purpose of biasing the bunter 17 toward operative position and holding the latch in engagement with the plate. The parts are normally stationary in the position shown by Figs. 3 and 4. While in such position, the bunter passes idly 40 beside the dog and does not interfere with the replenishing operation.

A shuttle feeler 26 (which may be integral with the latch 23) projects into the shuttle box in such position that it will normally (Fig. 3) not be engaged by the fully boxed shuttle. However, 45 should the shuttle box to a greater depth than usual it will engage the shuttle feeler and move the latter in such direction as to release the latch. This may occur on any pick, during or 50 prior to a call for replenishment. Promptly upon release of the latch the spring 25 pulls the bunter to the right, to the position shown by Figs. 1 and 2. It will be apparent that the bunter will stay in such position until it is manually reset.

Once the bunter has moved as just described 55 filling replenishment cannot take place, for if the dog 13 is moved upwardly it will be again forced downwardly before replenishment, through engagement of the dog 21 by bunter 17. Then, 60 as soon as the filling supply is entirely exhausted the loom will stop, whereupon the defective operating condition may be repaired and the revoking device manually reset.

Having fully disclosed the preferred embodiment of my invention, I claim:

1. In a filling replenishing loom, the combination of the lay, a shuttle, a shuttle box, filling replenishing means, a normally stationary shuttle feeler capable of being moved by said shuttle when the latter enters said shuttle box to a more 70 than normal depth, and means controlled by

said shuttle feeler for rendering said filling replenishing mechanism inoperative.

2. In a filling replenishing loom, the combination of the lay, a shuttle, a shuttle box, filling 5 replenishing means, a shuttle feeler carried by the lay and normally stationary thereon, said shuttle feeler being engageable and movable by said shuttle when the latter enters said shuttle box to a more than normal depth, and means controlled by said movement of the shuttle feeler to 10 render said filling replenishing means inoperative.

3. In a filling replenishing loom, the combination of the lay, a shuttle, a shuttle box, filling 15 replenishing means, means for rendering said replenishing means inoperative, a latch normally holding said preventing means out of operation, and a shuttle feeler for releasing said latch when said shuttle enters said shuttle box to a more than normal depth. 20

4. In a filling replenishing loom, the combination of the lay, a shuttle, a shuttle box, filling 25 replenishing means including a dog which is movable to and from operative position, means for removing said dog from said position prior to a replenishing operation when said shuttle enters said shuttle box to a more than normal depth, said last mentioned means including a bunter 30 movable on the lay to and from operative position, and means for holding said bunter in operative position until it is manually removed therefrom.

5. In a filling replenishing loom, the combination of the lay, a shuttle, a shuttle box, filling 35 replenishing means, means including a bunter movable to and from position where it renders said filling replenishing means inoperative, a latch for holding said bunter out of said position, means for releasing said latch when said 40 shuttle enters said shuttle box to a more than normal depth, and means operative upon release of said latch to move said bunter to said position and hold it in such position until manually released therefrom. 45

6. In a filling replenishing loom, the combination of the lay, a shuttle, a shuttle box, filling 50 replenishing means including a dog which is movable to and from operative position, a lay bunter engaging said dog to effect filling replenishment, a second bunter slidably along the lay to and from position where it removes said dog from said position prior to a replenishing operation, and means operative to move said second bunter to its said position when the shuttle enters 55 said shuttle box to a more than normal depth.

7. In a filling replenishing loom, the combination of the lay, a shuttle, a shuttle box, filling 60 replenishing means including a transfferer and a dog pivoted thereto, means for moving said dog to transffering position and means for removing said dog from said position when the shuttle enters said shuttle box to a more than normal depth, said last mentioned means including a bunter 65 movable along the lay, a latch for holding said bunter out of operation, a shuttle feeler for releasing said latch, and means operable upon release of said latch for moving said bunter to operative position. 70

JONAS NORTHRUP.
